CLAIM

The ornamental design for a body joint support device, as shown and described.

DESCRIPTION

FIG. 1 is a perspective view of the body joint stability device showing my new design according to a first embodiment of the present disclosure;

FIG. 2 is a front view thereof;

FIG. 3 is a rear view thereof;

FIG. 4 is an enlarged left side view thereof;

FIG. 5 is an enlarged right side view thereof;

FIG. 6 is a top view thereof;

FIG. 7 is a bottom view thereof;

FIG. 8 is a first perspective rear view thereof;

FIG. 9 is a second perspective rear view thereof;

FIG. 10 is a third perspective rear view thereof;

FIG. 11 is a perspective view of the body joint stability device showing my new design according to a second embodiment of the present disclosure in which the relative lengths of the extension portions to which the adjusting straps are attached are different from that shown in FIGS. 1-10;

FIG. 12 is a front view thereof;

FIG. 13 is a rear view thereof;

FIG. 14 is an enlarged left side view thereof;

FIG. 15 is an enlarged right side view thereof;

FIG. 16 is a top view thereof;

FIG. 17 is a bottom view thereof;

FIG. 18 is a first perspective rear view thereof;

FIG. 19 is a second perspective rear view thereof; and,

FIG. 20 is a third perspective rear view thereof.

Broken lines in the drawings show portions of the body joint support device that form no part of the claimed design.
